UNITED STATES PATENT OFFICE.

SAMUEL C. BOND, OF HOLLYOAK, DELAWARE.

BOTTLING MACHINE.

Application filed October 5, 1923, Serial No. 666,758. Renewed April 1, 1927.

This invention relates to machines for filling and capping bottles particularly to power operated machines of the type wherein the bottle is filled with carbonated water, with or without the addition of a flavoring syrup, and capped by the machine immediately after filling.

The principal object of the present invention is to provide a simple and efficient machine of this type wherein a plurality of bottles are simultaneously acted upon, one bottle being given its proper amount of syrup while the next preceding bottle is being filled with the carbonated water and capped, the raising of the bottles being simultaneously performed by power driven means automatically timed to perform the various operations in the proper sequence.

A further object of the present invention is the provision of means for filling and capping a bottle with a minimum of labor on the part of the attendant, the construction of the machine being such that the attendant is able to control the operation of the machine by a foot treadle so that he may have both hands free for the handling of the bottles.

Still further objects of the present invention reside in the specific details of several of the parts of the machine as more particularly pointed out in the specification following and definitely recited in the claims.

In the accompanying drawings.—

Figure 1 is a side elevation of the machine embodying the present invention.

Fig. 2 is a vertical section taken centrally of the filler head and syruping device.

Fig. 3 is a plan view of the parts shown in Fig. 2.

Figs. 4, 5, 6, and 7, are vertical sectional views through the bottom of the filler head showing the positions taken by the different parts during the cycle.

Fig. 8 is a vertical section through the bottom of the machine showing particularly the cam mechanism and its connected parts.

Fig. 9 is a rear elevation of the base with part of the casing broken away in order to illustrate more clearly the clutch operating mechanism and a portion of the operating cam.

Fig. 10 is an elevation of the clutch drive hub and timing ring and showing the position of the clutch pin proper in dotted lines.

The base 10 is a substantially rectangular casing enclosing the driving mechanism and supporting at its upper end a column 11 which in turn supports the filler head 12 and the hopper 14 which discharges the sealing caps to the filler head 12 through the chute 15.

The base cover 17, secured to the base in any desired manner as by the bolts 18, encloses the lower portion of the bottle raising mechanism, the parts visible in Fig. 1 being the bottle holder 19 which is held against rotation by the guide 20 on the column 10 and which may be adjusted on the head 22 which reciprocates a constant distance, by means of the screw 23, having a manually operated wheel 24 whereby the bottle holder may be regulated to suit bottles of various heights.

The filler head 12 is cylindrically bored as shown in Fig. 2 to receive a hollow cylinder 25 having a slight reciprocating movement as later described and is counterbored at the lower end forming a shoulder 26 against which is held the cylindrical valve casing 27 which guides an annular member secured to the cylinder 25, supports the admission valve assembly and provides a passage for the conveying of the carbonated water to the bottles.

The valve casing 27 contains a valve mechanism adapted to be operated by the valve handle 29 to admit carbonated water under pressure or to permit of the shifting operation which is necessary in filling bottles with liquids having gas under pressure therein. The carbonated water or the liquid under pressure is supplied through a rear fitting 30, Fig. 3, from any suitable source of supply, and its entrance into the filling chamber is normally prevented by a tubular valve 31 seating against the inner end of the valve casing or a suitable seat formed in the valve head, and if desired having an intermediate fiber washer 32, said valve being held against its seat by a spring 33. The valve is adapted to be brought away or lifted from its seat by the head of a secondary valve plunger 34 which at its outer end is connected with the valve end 35 controlled by the handle 29. The plunger 34 is tubular and provided with connected ports 36 in proximity to its ends, the port near its inner extremity being so located

that when the plunger is pushed inwardly it will be opened to the filling chamber, but when the plunger is drawn back until its

head seats against the fiber washer on the main valve, the port will be closed.

The port at the outer end of the plunger is in communication with the atmosphere or 5 waste pipe and as a convenient and desirable construction the valve casing is provided with an exhaust connection 37 which communicates with the exhaust pipe 38 whereby any sniffling exhaust will be 10 conveyed down through that pipe and escape at an unobjectionable point. For preventing communication between the liquid inlet and the sniffling exhaust the valve casing is provided with a front packing washer 39 15 held to its seat and in position to engage the tubular portion or sleeve of the main valve by a transversely apertured long follower 40 and the projection of the valve end 35 with which the plunger is connected is surrounded 20 by a packing washer 41 which is held in place by a short follower and lock nut 42. The whole arrangement is such that when the valve handle is moved in one direction or so as to draw the valve end outwardly, the 25 main valve will be lifted from its seat and carbonated liquid allowed to enter the filling chamber, but upon moving the valve handle in the opposite direction, the main valve will be seated or allowed to remain on 30 its seat and the supplemental valve will be opened, putting the filling chamber into communication with the exhaust through the two ports in the sniffling valve plunger.

The filler head is provided with a pad for 35 the attachment of a bracket 43 in which the syruping device is mounted. This syruping device comprises preliminarily a measuring cylinder 44 which is vertically movable in the bracket but held against rotation therein, 40 and within the cylinder there is a weighted piston 45, the upward movement of which piston in the cylinder is limited by an accurate stop mechanism which is readily adjustable from the exterior so as to regulate the 45 volume of syrup accommodated in the cylinder in any one charge. For admitting syrup to the cylinder, it is provided on the rear side with a syrup supply fitting 46, Fig. 3, connected with any suitable source of supply 50 and having sufficient hydrostatic head to elevate the piston. This syrup supply fitting 46 communicates with the interior of the cylinder through an inlet port 47, Fig. 2, opening downwardly and adapted to be 55 closed at certain times, if so desired, by a vertically movable valve 48. When the valve is in the position shown in Fig. 2 the inlet port 47 is in open communication through the intercommunicating passage 49 with the 60 cylinder below the piston, and the entering syrup will raise the piston to the limit permitted by the stop mechanism. The syrup is permitted to escape from the cylinder into the bottle when the valve 48 is lifted by con-

tact with the bottle and for this purpose the 65 valve 48, while normally seating so as to close the exit, will, when raised, permit the syrup to flow into the discharge port 50 and out at the lower end of the valve stem. The lower or external end of the valve stem is 70 provided with the usual cone-shaped seat for the mouth of the bottle and is normally held so as to close the exit port by means of a coil spring 51 confined between the conical mouth piece and a recess in a valve nut 52 75 screwing into the lower end of the cylinder.

The stop mechanism for regulating the volume of syrup measured, consists of a cylindrical gage nut 53 screwing into the upper end of the cylinder and at its lower edge 80 forming the stop for arresting the upward movement of the plunger or piston. The relation of the pitch of the screw threads to the size of the cylinder is such that a complete turn of the gage nut will vary the size 85 of the measuring chamber to accommodate a definite volume of liquid, say, for example, one-fourth ounce, and gage marks are provided on the nut for indicating each particular rotation and the volume which will be 90 measured at each point. In addition, the periphery of the nut and the cylinder with which it cooperates are divided into eight divisions, each of which indicates one thirty-second of an ounce, and in order to retain 95 the nut accurately and positively in its adjusted position with relation to the cylinder, vertical apertures are formed in the threaded portion of the two members, as shown at 54, in Fig. 3, for the accommodation of a locking pin 55, thus providing for the most accurate adjustment and the retention of the parts in their adjusted position with the greatest degree of certainty.

As a convenient construction the piston proper is preferably a relatively heavy body, as shown at 45, and this is surmounted by a leather packing 56 confined between the body 45 and a follower 57, the parts being held together by a screw-threaded handle 58 located 100 within the cylinder and gage nut, as shown clearly in Fig. 2.

The weight of the piston effects the discharge of the measured quantity of syrup 105 when the exit valve is opened by the engagement of the bottle mouth with the seat at the lower end of the valve, and by making the cylinder itself vertically movable in its bracket, any variation in the height of the bottle is readily accommodated and the only 110 precaution necessary to observe is that the spring holding the valve closed should be of less strength than that required to elevate the cylinder. In other words, the weight of the cylinder is largely in excess of the 115 strength of the spring and sufficient not only to overcome the spring but also to overcome the hydrostatic head of the syrup which 120 125

would tend to reseat the valve or to open the valve when moved sufficiently far to close the inlet port.

Within the hollow cylinder 25 is a vertically movable plunger 60 held at the bottom of the cylinder 25 by means of a heavy spring 61 confined between the disk-like head 62 of the plunger and the cap 63 which is threaded to the hollow cylinder 25 and is provided at its lower edge with an annular overhanging skirt 64 to prevent dirt finding its way into the filler head 12. At the top of the cap 63 are a pair of lugs 65 receiving a pin 66 affording a pivotal connection for the link 67 connecting the cap and cylinder with the lever 68 pivoted as at 69 to a lug 70 extending from the upper portion of the column 10.

Upon upward movement of the longer arm of the lever 68, the cap 63 is depressed and this cap being threaded to the hollow cylinder 25, the latter is lowered until the conical throat member 72 secured thereto comes in contact with the crown ring 73 which is permanently secured to the valve casing 27. Should the plunger 60 meet opposition, the spring 61 permits it to remain still while the hollow cylinder 25 moves downward as will be more fully described later.

The throat gasket 75 is of the shape best seen in Figs. 2 and 4 being somewhat U-shaped in cross section having a groove 77 in its outer periphery about midway of its length thus rendering it much easier to compress the gasket into sealing contact with the neck of a bottle than when using a solid annular gasket as has been the previous practice.

This gasket 75 is held between the crown ring 73 and the lower end of the valve casing 27 by means of the annular bottom cap 78 and by its natural resilience holds the crown ring against the valve casing and the thereto attached crown ring against the shoulder 26 except at such times as these parts are moved downwardly by virtue of the pressure exerted by the throat 72 which has a lower rounded lip 79 engaging a leather washer 80 set in a groove in the upper face of the crown ring 73 and affording a gas-tight seal.

The valve casing 27 is slotted as seen in Figs. 4 to 7 and in such slot is mounted a cap stop 82 pivoted as at 83 and movable about such pivot by contact with the rounded lip engaging the foot 85 of the cap stop lever aid by the upper bead 86 of the throat engaging the hooked end 87 of the cap stop. Referring particularly to Figs. 4 and 5 it will be noted that as the hollow cylinder 25 descends carrying with it the throat 72 the cap stop foot 85 will be moved outwardly and the annular throat 72 will position a cap such as 88 concentrically of the axis of the throat and plunger and at such time the upper bead or rim 86 of the throat lies in the hollow below the hooked end 87 of the cap stop lever in such position as to move the

foot 85 of the cap stop inwardly to engage an on-coming cap 85 delivered through the chute 15 on upward movement of the cylinder 25.

Power for operating the parts of the machine is supplied through the pulley 90 on the shaft 92 mounted in suitable bearings in the frame or base 10 and having a drive pinion 93 constantly driving the gear 94 keyed to the clutch hub 97, the latter being rotatably mounted on the non-rotating central main bearing 98 centrally mounted in the base 10 and locked in position by the set screw 99.

The main driving cam 100 has an extended hub 101 which houses the slidably mounted clutch pin 103 which is constantly urged towards the clutch hub 97 by the spring 104 but which is held against tension of the spring 104 by a wedge 105, the point of which normally engages a slot in the upper face of the clutch pin holding it retracted.

Rotation of the cam 100 is controlled by movement of the clutch pin 103 which in turn is controlled by the wedge 105 pivoted to the base 10 as at 108 so that upon depression of the foot treadle 109 fast to the shaft 110 by virtue of the link 111 and arm 112 the wedge 105 will be raised out of the slot of the clutch pin and the latter may move forward to engage the clutch hub 97 whereby the cam 100 will be rotated.

A second wedge 115 mounted radially with respect to the treadle shaft 110 moves simultaneously with the wedge 105 in such manner that when one is raised out of contact with the annular groove 116 in the extended hub 101 of the cam the other wedge will be brought into contact with the bottom of such groove and in such position as to retract the clutch pin as soon as the latter rotates into contact with the point of the wedge. As shown in Fig. 9 the upper wedge 105 is in contact with the hub 101 and the clutch pin and is held in such position by the spring 118 engaging with the bell crank lever 119 to which the wedge 105 is connected. Depression of the treadle raises the lever 105 and lowers the lever 115 but upon removal of the foot in the treadle the spring 118 restores all these parts to their original position.

The cam is double faced having cam grooves in opposite sides each guiding a roller, the roller 120 in the rear groove of the cam controlling the movement of the hollow cylinder 25 and the cap discharging mechanism of the hopper while the similar roller 121 in the front groove of the cam controls movement of the bottle support 19.

The shaft 122 upon which the roller 121 is mounted is pivotally secured to a piston 123 which reciprocates in the cylindrical bore of the base cover 17. The head 22 is operated from the piston 123 through the spring 125 which surrounds a spindle 126 threaded to the member 22 and locked against movement.

therewith as by the set screw 127. I find it convenient to place a wear sleeve 128 between the upper portion of the cover and the bottom of the skirt of the member 22 thus preventing undue wear of the permanent parts of the machine. As is obvious should the bottle carrier 19 be brought to rest before the end of the travel of the piston 123 the spring 125 will be compressed.

10 It sometimes happens that the operator fouls a bottle against the bottom cap of the filler head in which case the spring 125 is compressed to an excessive extent and unless some provision is made for such emergency the 15 breaking of a bottle while the spring is under this extreme tension might damage the machine by the violence of its return action. To meet this emergency I form a dashpot at the 20 end of the spindle 126 forming a cylindrical 25 recess 130 connecting with the narrower portion of the spindle through the hole 133 and I close the bottom of the cavity by means of a ball 134 and fill the base 10 with lubricating oil up to the level of the small pet cock 135 30 shown in Fig. 1. Now when the piston 123 rises after the bottle carrier 19 and spindle 126 are brought to rest a vacuum is formed between the shoulder 127 of the piston and the larger diameter at the bottom of the spindle. 35 Oil is therefore drawn past the ball 134 and is discharged into the annular cavity between the piston and spindle through the radial passageway 133. Should a bottle break with the spring under extreme tension the spindle 40 could not snap up into contact with the piston without first discharging this oil, the discharge being regulated through a small hole (not shown) connecting the annular chamber with the base and restricting the speed of return in exactly the same manner as in a door check. While the dashpot action is of but 45 little value in the ordinary operation of the machine it is of extreme importance in case of emergency.

45 Referring now particularly to Fig. 10 the clutch pin 103 is shown in dotted lines with its corner resting upon the timing ring 137 which is held in definite angular relation with the clutch hub 97 by means of a spring 138 mounted in a bore in the clutch hub and engaging a 50 pin 139 on the timing ring. As the clutch hub 97 rotates in the direction shown by the arrow the engagement of the clutch head 103 with the timing ring 137 prevents engagement 55 of the clutch pin with the immediate adjacent slot in the clutch hub but as the clutch hub continues to revolve in the direction shown engagement may be made with the next adjacent slot, the clutch pin then carrying the 60 timing ring against the tension of the spring 139 until engagement of the clutch pin and clutch hub is effected.

The operation of the device is as follows: The attendant first fills a bottle with syrup 65 and transfers this bottle to the filler head

and places a second bottle in position for cooperation with the syruping device; the operation then being continuous, the operator shifting the bottles in turn from the syruping device to the filling device. When 70 the syruped bottle is beneath the filler head the treadle 109 is depressed raising the wedge 105 and allowing the clutch pin to move rearwardly to lock the cam hub to the 75 constantly rotating clutch hub 97. Movement of the cam raises both bottles, the bottle beneath the filler head being raised from the position shown in Fig. 6 where it was placed by the operator to the position 80 shown in Fig. 7.

Just previous to the parts assuming the position shown in Fig. 5 the bottle cap holder 14 has discharged a cap through the chute 15 and into position on the crown ring 73 the opening in which is of such size as to 85 readily permit exit of a crimped cap while barring passage of an uncrimped cap. The movement of the cam which causes the bottle to rise simultaneously lowers the throat 72 by means of the rod 140 which is pivoted to 90 the lever 68 at its upper end and which carries the cam roller 120 at its lower end and then centers a cap 88 over the bottle 141 and also moves the next succeeding cap 142 back into the chute 15. A slight further movement of the roller 120 and rod 140 lowers the hollow cylinder 25 and the throat member 72 into sealing contact with the crown ring forcing the valve cylinder 27 downward and reducing the internal diameter of the sealing gasket 75 compressing the gasket so that 95 it forms a sealing engagement with the bottle.

The operator now manipulates the handle 105 29 of the valve so as to first admit carbonated water and when the pressure is equalized movement of the handle in the opposite direction permits the escape of air the handle being continuously manipulated forwardly and backwardly until the bottle is 110 properly filled. At this time the operator releases the treadle and since the two wedges are restored to normal position the cam continues its rotation which was stopped by the withdrawal of the clutch pin 103 by the 115 wedge 115. Further rotation of the cam thus set in motion by release of the treadle forces the bottle up through the throat gasket and into contact with the sealing cap 88, the first contact being caused by the 120 plunger 60. As the bottle enters the contracting throat member 72 the plunger 60 is elevated against the spring 61 as shown in Fig. 6 and at this time and while the bottle is still rising the cam raises the throat 72 to such extent as to release the pressure on the 125 throat gasket 75 and parts now being in the position shown in Fig. 7 and the throat remains in that position while the bottle continues its upward movement and then de- 130

scends to a point where the top of the bottle is below the bottom of the cap port after which the throat 72 rises and the capped bottle and the various parts again assume their original position as shown in Fig. 4.

I secure uniform pressure on each bottle by restricting the distance between the top of the bottle and the filling head to that necessary for causing a slight further contraction of the compensator spring from that at which it is set, the actual distance being controlled by the normal travel of the bottle support without the bottle.

It will be noted from Figs. 4 to 7 that when the hollow cylinder 25 and throat 72 are in their lowest position the bottle carrier 19 has been raised less than half its travel and that between Figs. 6 and 7 the throat rises as the bottle rises but to a very much less extent. As shown in Fig 7 the bottle is at the extreme upper limit of its travel but the throat is midway of its travel having already risen to free the gasket from contact with the bottle neck.

What I claim is:

1. In a filler head, an axially movable valve casing, a sub-head movable with respect to said valve casing, a throat carried by said sub-head and movable within said valve casing, means within said valve casing to form a seal with said throat, and means operable upon movement of said throat into sealing engagement to form a seal about the neck of a bottle inserted within the filler head.
2. In a power operated bottle capping machine, a filler head, a contractile throat gasket within said filler head adapted to engage a bottle neck, a throat member having a conical bore therein to engage a cap to crimp same about a bottle, a valve casing surrounding

said throat member and movable by engagement therewith, means for supporting a cap in position to be applied to a bottle and a cap stop carried by said valve casing.

3. In a filler head, a hollow vertically movable sub-head, a throat secured thereto, a pivoted cap stop pivoted in the path of said throat, and cooperating means on said cap stop and said throat for positioning said stop for centering a bottle cap with respect to the axis of the filler head.

4. In a filler head, a hollow movable sub-head, a throat secured thereto, a pivoted cap stop, and means on said throat for rocking said pivoted cap stop for centering a bottle cap with respect to the axis of the filler head.

5. In a filler head, a hollow movable sub-head, a throat secured thereto, a pivoted cap stop adapted to have one end projected beneath the throat, and means on said throat adapted to engage the opposite end of the stop for rocking said stop on its pivotal center.

6. In a filler head, a hollow vertically movable sub-head, a throat secured thereto, a rigid pivoted cap stop movable into the path of said throat, and means for positioning said cap stop to center a bottle cap with respect to the axis of the filler head, said cap stop being positively actuated.

7. In a bottle capping machine, a filler head, a hollow movable sub-head, a throat secured to said head, means for successively supplying caps to said head, a pivoted cap stop, means on said throat for rocking said stop to center a cap with respect to the axis of the filler head, and a barrier formed by said throat for separating a cap positioned by said stop from the succeeding caps.

SAMUEL C. BOND.
